UNITED STATES PATENT OFFICE

148,418

DESIGN FOR AN INCENSE BURNER

Richard J. Howard, St. Louis, Mo.

Application July 31, 1947, Serial No. 140,635

Term of patent 14 years

(Cl. D29—23)

To all whom it may concern:

Be it known that I, Richard J. Howard, a citizen of the United States, residing in the city of St. Louis and State of Missouri, have invented a new, original, and ornamental Design for Incense Burners, of which the following is a specification, reference being had to the accompanying drawings, forming a part thereof.

Fig. 1 is a side view of an incense burner showing my new design.

Fig. 2 is a view of another side.

Fig. 3 is a view of the side opposite to that shown in Fig. 2.

Fig. 4 illustrates the side opposite to that shown in Fig. 1.

Fig. 5 is a fragmentary perspective view show-

ing a central cavity at the top surrounded by the four sides.

I claim:

The ornamental design for an incense burner, substantially as shown.

RICHARD J. HOWARD.
